(57) **CLAIM**

The ornamental design for an external appearance of a golf cart cooler, as shown and described.

DESCRIPTION

FIG. 1 is a perspective view of the external appearance of a golf cart cooler showing my new design, the broken lines showing the golf cart are for illustrative purposes only and form no part of the claimed design;
 FIG. 2 is a rear elevation view thereof;
 FIG. 3 is a side view thereof, the opposite side being a mirror image;
 FIG. 4 is a front elevation view thereof;
 FIG. 5 is a top plan view thereof; and,
 FIG. 6 is a bottom plan view thereof.
